C. H. STEPHENSON,
FIREPROOF WASTE PAIL,
APPLICATION FILED NOV. 23, 1909.

1,148,261.

Patented July 27, 1915.

UNITED STATES PATENT OFFICE.

CHARLES H. STEPHENSON, OF LYNN, MASSACHUSETTS.

FIREPROOF WASTE-PAIL.

1,148,261.

Patented July 27, 1915.

Application filed November 23, 1909. Serial No. 529,630.

To all whom it may concern:

Be it known that I, CHARLES H. STEPHENSON, of Lynn, in the county of Essex and State of Massachusetts, have invented certain new and useful Improvements in Fire-proof Waste-Pails, of which the following is a specification.

This invention relates to metallic waste receptacles, and is especially designed to provide a pail or receptacle for holding combustible material such as oily cotton waste, to obviate the liability of fire which may, in the contents of the receptacle, be communicated to anything outside of the receptacle. A further object of the invention is to provide a receptacle of this character which entirely dispenses with the use of solder or other material liable to be melted by such heat as might be caused from a fire inside of the receptacle.

Another object of the invention is to provide a receptacle of this character having a lid or cover which cannot be left open. This is because underwriters' requirements are that covers of waste receptacles shall automatically close.

Another object of the invention is to provide a receptacle of this character which will have a well-ventilated space below the bottom which supports the contained material.

Another object is to provide a structure which will prevent contact of the side of the receptacle with any inflammable surface such as a wood partition.

To these ends the invention consists in the construction and combination of the parts substantially as hereinafter described and claimed.

Of the accompanying drawings,—Figure 1 is a side elevation of a receptacle embodying my present improvements. Fig. 2 is a plan view of the same. Fig. 3 represents a section on line 3—3 of Fig. 2, on a larger scale. Fig. 4 represents a detail section on line 4—4 of Fig. 1. Fig. 5 is a detail perspective view of the construction for securing the fixed top section in place. Fig. 6 represents a section on line 6—6 of Fig. 5. Fig. 7 is a detail perspective view of a portion of the hinge pintle and adjacent portions of the lid or movable section of the top.

Similar reference characters indicate the same or similar parts in all of the views.

The body 10 is made of any suitable metal such as galvanized iron and may or may not be provided with spiral strengthening ribs 11. At the top is a wire reinforce 12 (see Figs. 3 and 4) over which the sheet metal of the body is rolled as at 10^a. At the lower edge is a wire reinforce 13 over which the material is rolled as indicated in Fig. 4.

The bottom 14 of the receptacle is formed with a vertical flange 15 seated between the outer and inner portions of the folded body part, rivets 16 being employed to firmly unite the whole together. This vertical flange 15 is of a height to locate the bottom 14 well above the lower edge of the body, so as to provide sufficient space to prevent dangerous radiation of heat downward upon any combustible material that might be beneath said bottom. This space is preferably ventilated by means of suitable holes 17.

The top of the receptacle comprises two sections, one of which, 19, is fixed, and the other section, 20, being movable and constituting the hinged cover or lid. The line of the hinge between the two forms a chord, and the arc formed by the outer edge of the section 19 is rolled over the rolled top of the body, and is formed with a tongue 21 at each end of the arc, said tongues being secured by rivets 22. The front edge of the section 19 is formed with a vertical flange 23, the lower edge of which flange is preferably rolled or doubled at 24 in Fig. 3. The rolled reinforced edge 24 strengthens the flange against lateral bending of its lower edge, and the flange being substantially at a right angle to the plane of the section 19, a very rigid structure is provided, due to said reinforced flange acting as a truss. The said flange 23 is furthermore rendered more rigid, and more firmly secured in place, by the tongues 25 at the ends of said flange, said tongues being turned or bent against the inner wall of the body and secured by rivets 26.

Secured to the section 19 are ears 27 (see Fig. 2) in which is mounted a pintle 28 carried by the hinged cover or lid 20. Said pintle is formed with inclined ends 29 for a purpose presently described. The hinged

cover 20 is provided with ears or rolled portions which embrace the pintle, these rolled portions comprising members 30 which embrace the straight portions of the pintle, and 5 members 31 which embrace the inclined ends 29 of the pintle, as clearly indicated in Fig. 7. The rolled portions 31 are, in reality extensions of the flange 32 of the cover or lid 20. Preferably this flange 32 is rolled as indicated at 32^a, to reinforce it and provide a smooth edge.

The reason for forming the pintle with the inclined ends is as follows: In the first place it is desirable that the hinged cover 15 or lid shall have as great an area as possible, considerably more than half of a circle. This necessitates the location of the pintle at a point where it forms a chord considerably to one side of the center of the entire 20 top. As it is desirable that the flange 32 of the lid shall fit as closely as possible, and have its rear ends so supported that they will be firm and rigid and not liable to get bent out of place, the inclined ends of the 25 pintle constitute reinforces for the two ends of the flange 32, holding those portions of said flange rigidly but sufficiently inclined outward so that they will not bind upon the top of the body of the can when the lid is 30 being raised, nor interfere with the closing of the lid.

I provide a combined handle and lid-stop as follows: A piece of strong strap iron or other suitable material is bent to form a 35 handle 33, one end of which is bolted as at 34 to the top of the receptacle. It is formed with a double portion 35 which is inclined forward of the vertical plane of the hinge of the lid, so that said lid can never be raised 40 beyond a position substantially such as indicated by dotted lines in Fig. 1, therefore rendering it impossible for the lid to be left open either accidentally or intentionally. Said double portion of the strip or strap 45 extends downwardly and rearwardly and is formed with a flat portion 36, bearing on the top of the fixed top section 19 and secured thereto as by a rivet 37. The extreme end may be formed as a tongue passing through 50 a hole in the lower part of the handle portion 33 and headed down as indicated at 38 as in Fig. 3. This structure not only provides a handle 33 by means of which the entire pail or receptacle may be lifted, but 55 the double portion 35 forms a stop for limiting upward movement of the lid and when the lid is closed, said double portion can be conveniently grasped by the hand and manipulated to enable the receptacle to be 60 rolled in a manner similar to that in which barrels are frequently rolled without laying them down upon their sides.

While the ribs 11 have been referred to as strengthening ribs, they possess a more

important function. Owing to the fact that 65 they project outward from the body 10, they make it impossible that the receptacle shall be placed close enough to any other object to exclude air. As a matter of fact they need not be continuous but in any event 70 lateral projections are provided which extend outward from the body of the receptacle sufficiently to prevent the receptacle from being left in contact with an inflammable wall such as a wood partition or a door. 75 Consequently, the receptacle as a whole is so constructed that neither the bottom 14, nor the side of the body 10, these being the portions which are liable to become very hot 80 in case the waste in the receptacle should catch fire, from communicating sufficient heat to any surrounding or adjacent body so as to cause a fire.

I claim:

1. A metal receptacle having a top comprising a fixed section having its inner edge provided with a down-turned strengthening flange continuous from end to end, a lid section hingedly mounted on the upper surface of the fixed section, and a metallic combined 90 handle and lid stop connected both to the top of the fixed section and to the side of the body of the receptacle, said stop overhanging the axis of the hinge connection.

2. A metal receptacle having a top comprising two sections hinged together, one of the sections having portions riveted to the outer side of the body of the can, and having a downwardly extending flange provided with tongues riveted to the inner side of the 100 body.

3. A cylindrical metal receptacle having its upper end provided with a top comprising a fixed section and a movable section, the fixed section having a rigid upwardly projecting handle, said handle being narrow to enable it to be grasped by one hand to shift the position of the receptacle by tilting it and then rolling it aside.

4. A cylindrical metal receptacle having its upper end provided with a permanent top closure comprising a fixed section and a lid hinged thereto, the fixed section having a rigid handle projecting upwardly in an inclined direction over the hinge of the lid, said handle being narrow to enable it to be grasped by one hand, said handle serving as a stop to limit upward movement of the lid, as well as used to tilt and roll the receptacle aside.

5. A metal receptacle having a top comprising a fixed section and a movable section and a pintle connecting the two, the movable section having a flange, and the ends of the pintle being bent and secured to 125 said flange.

6. A metal receptacle having a fixed top section, a pintle supported by said top sec-

tion, said pintle having downwardly bent ends, and a lid section connected to said pintle and having a flange, the end portions of said flange having ears bent around the 5 downwardly extending end portions of the pintle.

In testimony whereof I have affixed my signature, in presence of two witnesses.

CHARLES H. STEPHENSON.
